UNITED STATES PATENT OFFICE

2,111,170

MACHINE FOR FINISHING GEARS

Robert S. Condon, Rochester, N. Y., assignor to
Gleason Works, Rochester, N. Y., a corporation
of New York

Application September 10, 1935, Serial No. 39,952

22 Claims. (Cl. 51—26)

The present invention relates to machines for finishing and testing gears, particularly to machines of the combination type for lapping and testing or burnishing and testing gears. In a more specific aspect, the invention relates to machines for lapping or burnishing and testing spiral bevel and hypoid gears.

One of the principal objects of this invention is to provide an automatic machine for lapping and burnishing spiral bevel and hypoid gears, which will operate according to the basic principles of the U. S. patent of Alton P. Slade, No. 1,796,484 of March 17, 1931 and which will be of simplified and improved construction as compared with the automatic machine of the joint U. S. patent of myself, E. W. Bullock and Eyyvind Finsen, No. 1,881,999 of October 11, 1932.

Still another object of the invention is to provide a machine of the type in which the relative positions of the meshing gears are changed during lapping in order to effect the lapping operation and to obtain a suitable localization of tooth bearing, in which the amount of back-lash between the gears may be controlled and, if desired, maintained substantially constant throughout lapping.

Another object of the invention is to provide a gear burnishing or lapping machine in which the lapping or burnishing operations on opposite sides of the teeth can be effected at different rates.

Still another object of the invention is to provide in a combined burnishing or lapping and testing machine, improved means for both protecting the operator against injury and preventing damage to the gears being burnished, lapped or tested.

Other objects of the invention will be apparent hereinafter from the specification and from the recital of the appended claims.

In the machines of the type described in Patent Nos. 1,796,484 and 1,881,999, lapping or burnishing of a pair of spiral bevel or hypoid gears is accomplished by rotating the pair of gears to be lapped or burnished in mesh and simultaneously moving one of the gears in directions both longitudinal of the axis of the other gear and transversely thereof.

In burnishing, the teeth of one gear are bottomed in the tooth spaces of the other and are held in engagement by spring pressure and as the one gear moves longitudinally and transversely of the other gear, the springs yield and cramping of the teeth of the gears is avoided.

In lapping, however, it is not desirable to mesh

the gears so that the teeth of one bottom in the tooth spaces of the other.

It has been necessary heretofore, then, to set up the gears with sufficient back-lash to avoid interference at the ends of the teeth as one gear moves first toward the small end and then toward the larger end of the teeth of the other gear. This has meant, of course, that in the central position, the amount of back-lash between the gears will be more than necessary and accordingly the lapping action will be reduced.

In the machine of the present invention, provision is made for mechanically and automatically maintaining a uniform amount of back-lash between the gears during lapping in all positions of their relative movement. Thus the most effective lapping action can be obtained throughout the whole of the lapping operation and therefore the speed of the lapping operation can be increased.

In the machines of both the patents mentioned, the relative longitudinal and transverse movements between the meshing gears are effected by oscillation of a carrier in which one of the gears is eccentrically mounted. This same construction is retained in the present machine. In order to obtain the desired tooth bearing on opposite sides of the teeth, practice has demonstrated that it is desirable to run the meshing gears together first in one direction and then in the other and that during rotation in opposite directions, the carrier should be oscillated through different angles and at different rates. This is because of the difference in the effects of lapping or burnishing on the drive and coast sides of the gear teeth.

In the machines of both prior patents mentioned, two different cams were employed to produce the differing oscillating motions required for the burnishing or lapping of the opposite sides of the gear teeth, and it was necessary to shift these cams manually or automatically, at the time of reversal of the direction of rotation of the gears, to bring them successively into operating position. The gears were run for a given period in one direction with one cam producing the oscillating motion of the gear carrier, then this cam was shifted out of position and the other cam brought into operative position, the gears were reversed and then run in the opposite direction with the second cam producing the oscillating motion of the gear carrier, and then at the end of a given period the machine was stopped. In the burnishing or lapping of either side of the gear teeth, the carrier-control cam made one or more revolutions and hence in the

lapping or burnishing of the two sides of the teeth, the cam shaft made a plurality of revolutions. Hence, it was necessary in both prior machines to employ an automatic stopping mechanism having a counter arrangement to stop the machine when the lapping or burnishing operation was completed.

In the preferred embodiment of the present invention, a single cam is employed to control the oscillating motions of the carrier in the finishing of both sides of the gear teeth. One-half of this cam controls the oscillating motion of the carrier during finishing of the drive side of the teeth and the other half of the cam controls the motion of the carrier during finishing of the coast side of the teeth. It is not necessary to shift from one cam to another between the operations on the opposite sides of the teeth. Moreover, in a single revolution of the cam shaft, the whole cycle of operation of the machine is completed. Hence the expensive automatic stopping mechanism heretofore required can be and is eliminated. Means is provided instead for reversing the gears and stopping them directly from the rotation of the cam shaft. The rates of the burnishing or lapping operations on the two sides of the teeth are controlled by separate sets of change gears which drive the oscillating cam at different rates during the lapping or burnishing of opposite sides of the teeth.

In the embodiment of the invention illustrated in the drawings, the gear spindle is journaled in a sleeve or quill which is axially movable in the oscillatable carrier. For lapping, this sleeve is moved axially to maintain a controlled amount of back-lash by oscillation of a screw which threads into a nut that is secured to the sleeve. This provides a very simple, compact construction. For burnishing, the screw and nut are omitted but the gears are held in mesh with the teeth of one bottoming in the tooth spaces of the other by coil-springs which operate directly upon the quill or sleeve. This constitutes an improvement in burnishing machine construction, because the springs are able to act more directly upon the gears than in the prior machines, and there is less likelihood of vibration or chatter.

A further improvement of the present machine particularly valuable for lapping, is an improved back-lash brake. This is in the form of a hydraulic pump driven from the gear spindle. The pump forms part of an open hydraulic system and is connected to a sump so that when the pump is in operation, it will pump liquid out of the sump and discharge it back into the sump again. The amount of load or resistance to be applied to the gears is determined by the setting of a relief valve which controls the discharge from the pump. The greater the liquid pressure required to open the relief valve, the greater the resistance to the turning of the pump and, therefore, the greater the resistance to the rotation of the gears, that is, the greater the load applied to them. This type of brake has been found very much more satisfactory than the friction type of brake used on previous machines. Friction brakes are liable to wear and if oil or grease get on the friction surface, slippage, or grabbing will occur. The lapping of gears is a precision operation and the improvement in the back-lash brake makes possible a more accurate product.

As indicated above, the machine of the present invention may be used for lapping or burnishing and testing. For testing, the gears are simply run together on center and no oscillating or axial

motions are employed. A guard is, of course, provided on the machine to enclose the gears during lapping or burnishing. Safety features have been incorporated in the electrical circuit of the machine so that for lapping, the guard must be closed and the oscillating cam must be in operating position while for testing, the guard must be open and the oscillating cam must be out of operative position. As a further safety feature, to prevent any possibility of the operator getting his hands caught between the gears, during testing, provision is made so that the operator must keep one hand on a push button during the whole of the test in order to keep the machine running. His other hand, of course, will be out of the way as it will be operating a hand brake to apply the load required to test the gears.

In the drawings:

Fig. 1 is the side elevation, with parts broken away, of a combination burnishing or lapping and testing machine constructed according to the present invention;

Fig. 2 is a plan view of this machine;

Fig. 3 is a longitudinal sectional view of the gear head of a machine arranged for lapping, the section being taken substantially on the line 3-3 of Figure 2;

Fig. 4 is a corresponding view of a machine arranged for burnishing;

Fig. 5 is an end view partly in section, of the gear head and supporting column taken at right angles to the section of Fig. 3;

Fig. 6 is a detail view of the contact members for imparting the oscillating and reciprocating motions to the carrier and quill, respectively, in the lapping machine;

Fig. 7 is a section approximately on the line 7-7 of Fig. 5, showing the cam shaft and details of the drive therefor;

Fig. 8 is a sectional view taken approximately on the line 8-8 of Fig. 7;

Fig. 9 is a view looking at the end of the gear head and showing the hydraulic back-lash braking mechanism;

Fig. 10 is a developed sectional view on the line 10-10 of Fig. 9;

Fig. 11 is a sectional view on the line 11-11 of Fig. 9;

Fig. 12 is a fragmentary sectional view showing in detail the mechanism for adjusting the pinion head;

Fig. 13 is a sectional view of the lapping guard, showing the piping for conducting the lapping compound on to the gears and the limit switch which insures that the guard is closed during a lapping or burnishing operation;

Fig. 14 is a fragmentary view taken at right angles to Fig. 13 and showing details of the distributing system for the lapping compound;

Figures 15 and 16 are side elevational views of typical cams for controlling the oscillating and axial movements of the carrier and quill, respectively;

Fig. 17 is a fragmentary sectional view on the line 17-17 of Figure 7;

Fig. 18 is a fragmentary sectional view on the line 18-18 of Fig. 7;

Figures 19 to 24 inclusive are diagrammatic views, illustrating how interference will occur during lapping at the ends of the teeth of the meshing gears in the shifting movements of one gear under oscillation of the carrier if some means are not provided to compensate for each interference, and

Fig. 25 is an electrical wiring diagram of the machine.

Referring now to the drawings by numerals of reference, 30 designates the base or frame of the machine. On this base or frame there are mounted, as in previous machines, a head 31 and a column 32 (Figures 1, 2, and 5). These are adjustable on the base or frame at right angles to one another to bring the gears to be lapped, 10 burnished, or tested into meshing engagement.

Journalized in anti-friction bearings 34 and 35 in the head 31 is the drive-spindle 36 of the machine. The pinion of the pair of gears to be burnished, lapped or tested, or if a special burnishing or lapping pinion is used, that pinion, 15 is secured to the drive-spindle 36. Any suitable chucking mechanism may be employed for securing the pinion to the drive-spindle. In the machine illustrated, a hydraulic chucking mechanism, 20 designated as a whole at 38 is employed for this purpose. As this chucking mechanism is of standard construction and forms no part of the present invention, it will not be described in detail here. The pinion spindle 36 is driven from 25 a motor 40 mounted in the base of the machine through pulleys 41 and 42 and the belting 43 connecting the same.

The column 32 is provided with vertical ways 45 (Figs. 5 and 7) on which the gear head 46 is 30 vertically adjustable. The means for adjusting the head 46 on the column 32 may be the same as employed in the machine of Patent No. 1,881,999 and for that reason will not further be described here.

35 The gear or driven spindle 48 of the machine is carried in this gear head 46. It is journalized on anti-friction bearings 49 and 50 in a sleeve or quill 51 and this quill is slidably mounted in an oscillatable carrier 52 (Figs. 3 and 5). The 40 mounting of the spindle 48 in the quill 51 and of the quill 51 in the carrier 52 is such that the axis of the spindle 48 is offset from the axis of the carrier but parallel thereto, that is, that spindle 48 is mounted eccentrically in the carrier. The carrier is journalized in plain bearings 54 and 55 formed integral with the head 46.

The gear G to be burnished, lapped or tested or, in case a special burnishing or lapping gear is used, that gear, is secured to the driven spindle 50 48. For securing the gear to the spindle, any suitable type of chucking mechanism may be employed. In the machine illustrated, a standard hydraulic chucking mechanism, designated as a 55 whole at 58 is employed, but as this mechanism is of known construction and forms no part of the present invention, it will not further be described here.

Mounted on the column 32 of the machine is a motor 60 (Figs. 1, 2, and 7). This motor drives 60 the carrier 52 and, during lapping, the reciprocating quill 51, as will now be described. The motor is connected by a suitable coupling 61 with a shaft 62 carrying the worm 63. This worm 63 meshes with a worm wheel 64 (Fig. 8) that is 65 keyed to a shaft 65. The shaft 65 is journalized on anti-friction bearings 66 and 67 in a bracket 73 which is secured to the column 32.

Splined to the shaft 65 are a pair of spur change-gears 68 and 69. These are secured 70 against a shoulder formed on the shaft by the nut 70, which threads on the shaft, and by the washers 71 and 72.

The spur-gears 68 and 69 mesh, respectively, 75 with spur-gears 74 and 75 (Fig. 7) which have splined connections, respectively, with the shafts

76 and 77. The gears 74 and 75 are held on their respective shafts by nuts 78 and 79, respectively, which thread on the shafts and by the washers which cooperate with these nuts.

The shaft 76 is journalized on anti-friction bearings 80 and 81 in the bracket 73. The shaft 77 is journalized on anti-friction bearings 82 and 83 in the bracket 73.

There is a spur gear 84 keyed to the shaft 76 and there is a spur gear 85 keyed to the shaft 77. These gears are adapted to be meshed selectively with a spur gear 87 (Figs. 7 and 8) that is integral with a sleeve 88. This sleeve is mounted to slide upon a shaft 90 that is journalized on anti-friction bearings 91 in the bracket 73 and on anti-friction bearings 92 in an arm 94 that is secured to the bracket 73 by screws 95.

The shaft 90 has a worm 96 formed integral with it that meshes with a worm-wheel 97 (Figs. 8 and 7). The worm-wheel 97 is keyed to a 20 sleeve 98 which forms a bearing for a sliding shaft 99. There are two pins 100 and 102 secured in the worm-wheel 97 to project from one side thereof.

Pivotedly mounted at 106 in the bracket 73 is 25 a yoke-member 105 having a long arm 103 and a short arm 104. In the rotation of the worm-wheel, the pin 100 is adapted to engage the long arm 103 of the yoke-member and the pin 102 is 30 adapted to engage the short arm 104 of said yoke-member, thereby shifting the yoke-member alternately in opposite directions about its pivot 106. The yoke-member carries opposed rollers 107 which engage in a recess or groove 108 formed between the shoulders 109 and 110 of the 35 sleeve 88. Thus, as the worm-wheel 97 rotates, the yoke-member 105 is rocked first in one direction and then in the other about its pivot 106 to engage the gear 87 alternately with the gear 85 (Fig. 7) and with the gear 84. The gears 84 40 and 85 drive the gear 87 in the same direction so that the worm-wheel 97 is driven in the same direction regardless of whether the gear 87 is engaged with the gear 85 or the gear 84, but the worm-wheel 97 is driven at one rate when the gear 84 is driving the gear 87 and at a different 45 rate when the gear 85 is driving the gear 87.

The external groove 108 in the sleeve 88 is wider than the rollers 107, which operate therein, for a purpose which will appear hereinafter. 50

To insure quick shifting of the yoke-member 105 and to insure that the gear 87 remains in contact with either the gear 84 or 85, which has previously been driving it, until the yoke-member 55 has been shifted so that there will be a continuous drive to the worm-wheel 97 at all times, a load and fire mechanism and a drag-detent are provided.

The yoke-member 105 is operated by a load 60 and fire mechanism comprising a plunger 115 that is housed in a bore in the bracket 73. This plunger is spring-pressed outwardly by a coil spring 116 and it has a V-shaped outer end or head 118 which engages the V-shaped head 119 of a stud 117 that is secured in the yoke-member 65 105. As soon as the yoke-member 105 is rocked past center in either direction, this load and fire mechanism operates to swing it on quickly and positively to the end of its movement.

The bore of the sleeve 88 is formed with two 70 conical recesses or grooves 120 and 121. The shaft 90 has a hole 122 drilled diametrically through it. There is a pin 123 mounted in this hole that has a conical head 124. A sleeve 125 telescopes on the pin 123 and this has a conical head 126. 75

The two headed members are adapted to engage in the recesses 120 or 121 depending upon the axial position of the sleeve 88 and they are pressed apart and into engagement with these recesses by a coil spring 127. The heads 124 and 126 are pressed by the spring 127 into engagement with one or the other of the recesses 120 or 121 depending upon the axial position of the sleeve 88 and act as a frictional drag on the sleeve to prevent its axial movement until positively shifted by the yoke-member 105.

As above described, the external groove 108 in the sleeve 88 is wider than the pins 107 which operate therein. Hence, during the first part 15 of the movement of the yoke-member 105 in either direction, no movement is imparted to the sleeve 88 and gear 87 and it is not until after the yoke-member has passed center and is being thrown on to the end of its movement by 20 the spring pressed plunger 115 that the sleeve 88 and gear 87 start to move. The double headed plunger 124—125 serves to hold the gear 87 in engagement with whichever of the gears 84 or 85 that has been driving it, until the yoke has 25 passed center. Then the momentum of the yoke under actuation of the spring-pressed plunger 115 is sufficient to overcome the frictional resistance of the drag-detent 124—125 and the sleeve 88 is moved on into its new axial position. The drag-detent serves to insure that the gear 87 remains in driving engagement with either the gear 84 or 85 until movement of the yoke on to its new position is insured. Thus 30 assurance is had of a drive at all times to the 35 worm-wheel 97.

The shaft 99 is slidably mounted in the sleeve 98 and in a plain-bearing 130 which is secured in a plate 140 that is secured in any suitable manner to one side of the column 32. Keyed to 40 the shaft is a disc 131 on whose hub is mounted a cam 132 which is secured to the disc 131 by screws 133. The periphery of the disc 131 is concentric with the axis of the shaft 99. The cam 132 may be of any suitable shape, one typical form of such cam being shown in Fig. 15.

135 denotes a roller which is mounted upon a stud 136 which is threaded into a cylindrical bar 138. The bar 138 is adapted to slide in a tubular guide formed in a bracket 139, which is secured to the plate 140 that is secured to the column 32. Either the cam 132 or the disc 131 may be engaged with the roller 135 by shifting the shaft 99 axially. During lapping or 50 burnishing the cam is engaged with the roller 135 while during testing the disc is engaged with the roller as will hereinafter appear.

Mounted in the bar 138 at the end opposite that which carries the roller 135, is a stud 142 on which is mounted a roller 143. The roller 143 60 engages one end of a contact-member or stud 144, that is adjustably mounted in the arm 145 of a yoke-member 146 (Figs. 6, 3 and 4). The yoke member 146 takes its bearing on the periphery of the carrier 52 and is secured to the 65 carrier 52 in any suitable manner to transmit motion to the carrier.

The contact-member 144 is held in engagement with the roller 143 of the bar 138 and the roller 135 of this bar is in turn held in engagement with the cam 132 by a spring (not shown) which operates to urge the carrier in one direction about its axis. The construction may be the same as shown in the Bullock et al. patent above mentioned. The contact member 144 is 70 adjusted axially in the arm 145 by rotation of

the handwheel 147 which is secured to a shaft 148 that threads into the arm and that abuts at its inner end against the opposed end face of the contact member 144. The extremity of the arm 145 is in the form of a split clamp and the contact member may be secured in any adjusted position in the arm by tightening the clamping lever 149.

From the above description it will be seen that when the cam 132 is engaged with the roller 135 and the shaft 99 is rotated, the cam 132 will impart a reciprocating movement to the bar 138 to oscillate the carrier 52 on its axis, thereby causing the gear to be swung about an axis eccentric of its own axis. Of course, when the disc 131 is engaged with the roller 135, the carrier will remain stationary despite the rotation of shaft 99 because the disc is concentric of the shaft.

The disc or cam selectively is brought into engagement with the roller 135 by moving the shaft 99 axially. Axial movement of the shaft is effected by movement of a lever 153 which is pivotally mounted at 157 on the column 32. This lever is formed at its short end with a yoke portion having pins 159 which engage in a peripheral recess formed in the shaft 99.

To insure that a cam 132 is engaged with the roller 135 when a pair of gears are to be lapped or burnished and that the disc 131 is engaged with the roller when a pair of gears are to be tested, a safety device is provided. This comprises a double-throw switch 196 (Figs. 7 and 25) which is mounted on the column 32 in such position that the roller 197 carried by its arm 198 is engaged by one of the pins 159 of the lever 153 to rock the switch arm when the shaft 99 is shifted in either direction. The function of this switch will be described more particularly hereinafter.

Keyed to the shaft 99 at one end thereof is a 40 sleeve 150 (Figure 7). This sleeve is journaled on anti-friction bearings 151 and 152 in the end-cap 154 of the bracket 139. Secured to the flange 155 of the sleeve 150 by screws 156 is a cam 158. This cam may be of any suitable conformation. One typical form of such cam is shown in Fig. 16.

The cam 158 is adapted to engage a roller 160 which is rotatably mounted upon a stud 161. The stud 161 is secured in one end of a cylindrical bar 162 which is slidably in a cylindrical guide 50 formed in the bracket 139 parallel to the guide in which the bar 138 slides.

This bar 162 is of reduced dimension at its outer end and engages the half-round end of a contact member or follower 164 which is rotatably adjustable in a sleeve 163 that is adjustably threaded in the arm 165 (Figs. 6 and 3). By rotating the contact member 180° from the position shown in Fig. 6 it can be thrown out of engagement with the bar 162 so as to render it inoperative. In this position its tip will engage the surface of the arm 166 which is secured to the bracket 139 (Fig. 7) by screws 167. The contact member 164 is held in either position of its adjustment by set-screws 168 and 169 which are 60 adapted to engage in longitudinal grooves 170 and 171 formed in the contact-member. The contact member is held against axial movement relative to the sleeve 163 by the nut 172 which is threaded on the outer end of the reduced stud portion of 70 the contact member.

The arm 165 is pivotally mounted at 174 (Fig. 5) in a guard 176 and has a depending portion (Fig. 3) which is keyed to a screw shaft 175 which is journaled in suitable bearings in the head 46 and 75

in the guard 176. The guard 176 is secured to the head. The screw shaft 175 has a threaded portion 177 which engages in a nut 178. This nut 178 is secured in a ring 179 which is rigidly held between the inner end of the quill 51 and a spacer member 180 that is secured to the sleeve or quill by screws 182. The spacer member 180 is also held against axial movement relative to the quill 51 by the sleeve 184 which is keyed to spindle 48 and which is formed with a flange 185 that engages in a circular recess formed in the spacer member 180. The sleeve 184 is held in position by the brake-drum 186 which is secured on the spindle 48 against axial movement relative thereto by the nut 187 that threads onto the spindle.

From the preceding description, it will be apparent that as the cam shaft 99 rotates, the cam 158 (Fig. 7) will impart a reciprocating movement to the bar 162 and this in turn will oscillate the arm 165 and screw 177 to move the quill 51 axially to and fro in the carrier 52, thereby imparting an axial reciprocating movement to the spindle 48 and the gear G mounted thereon.

The key 190 (Fig. 3) which is secured to the quill 51 by the screws 191 and the dowel 192 serves to transmit the oscillatory motion of the carrier 52 to the quill 51 and spindle 48 as the spindle rotates and the quill moves axially. The recess 194 in the carrier in which the key 190 engages is longer than the key to permit free axial movement of the quill in the carrier while maintaining the oscillating driving engagement between the two.

Coil-springs 195 are provided to take up backlash in the screw 178 and to urge the quill 51 continuously rearwardly in the carrier 52. These springs, which are provided at angularly spaced intervals around the carrier, are mounted in aligned openings in the quill and carrier and bear at one end against the spacer member 180 and at their opposite ends against the carrier.

The contact-member 164 (Figs. 5, 6, and 7) is held against one end of the bar 162 and the roller 160 is held in contact with the periphery of the cam 158 by action of the spring-pressed plunger 196 (Fig. 5). This plunger is housed in a bore in the guard 176. It engages a roller 197 that is secured by a stud 198 to the arm 165. A coil-spring 199 housed within a bore of the plunger 196 actuates the plunger.

In addition to the cams 132 and 158, there are a pair of cams 200 and 201 carried by the cam shaft 99. The cam 201 is keyed to the cam shaft by the same key which serves to secure the disc 131 to the cam shaft (Fig. 7) and the cam 200 is pinned to the cam 201. The disc 131 and the cams 201 and 200 are held against axial movement on the shaft by the nut 293 which threads onto the shaft. The cam 200 operates a double-throw switch which controls the direction of rotation of the gears being burnished, lapped or tested and the cam 201 controls a single throw switch that effects the stopping of the machine at the end of the burnishing, lapping or testing operation. The double throw switch is shown in Fig. 17 and the single throw switch in Fig. 18.

The double throw switch comprises a body portion 205 and a pair of blade-arms 206 and 207 that are pivotally mounted at 208 on the body portion 205. The body portion 205 is itself pivotally mounted upon a pin 204 in a switch housing 209 which is suitably mounted on the bracket 139. There is a bar 216 mounted on the blade-arm 206 and this arm carries a pair of contact

points 210 and 211 (Figs. 17 and 7). There is a bar 218 mounted on the blade-arm 207 and this bar carries a pair of contact points 212 and 213. A plunger 214 is slidably mounted in the body portion 205 of the switch. A coil-spring 215, which is interposed between the plunger 214 and the blade-arm 206, serves to urge the plunger 214 downwardly and outwardly of the body portion 205 and also serves to urge the contact points 210 and 211 towards contacting engagement with a pair of terminals 217. A coil-spring 219 which is interposed between the body portion 205 of the switch and the blade arm 207 serves to urge the contact points 212 and 213 into contact engagement with the terminals 220.

The body portion 205 of the switch is urged in one direction about its pivot 204 by a spring-pressed plunger 222 which is pivotally connected at 223 to the body portion 205 of the switch. This plunger is housed and slides in an opening 224 in the end plate 225 which is secured to the bracket 139. The coil-spring 226 which surrounds the reduced stem portion of the plunger 222 and is housed in the opening 224 serves to actuate the plunger.

The double blade switch is tripped by a spring-pressed plunger 230 which is mounted to slide in an opening 232 in the end plate 225. A coil spring 233 is housed in this opening 232 and surrounds the stem of the plunger 230. This spring 30 is interposed between a shoulder formed on the plunger and a guide-plate 235 which is secured in any suitable manner to the end plate 225.

There is a teat 236 formed on the projecting portion of the plunger 230 at one side thereof. 35 The tip of the plunger 214 is beveled off and the teat 236 has an oppositely beveled tip to cooperate therewith. As the cam shaft 99 rotates in the direction indicated by the arrow in Fig. 17, the cam 200 engages the end of the plunger 230 and 40 forces this plunger inwardly in the bore 232 against the resistance of the spring 233. In this inward movement of the plunger 230, the plunger 214 rides up and over the teat 236 and the teat engages behind the plunger 214. When the cam 45 200 rides off of the end of the plunger, the spring 233 forces the plunger outwardly but because of the engagement of the teat 236 with the plunger 214, this outward movement of the plunger 230 rocks the body portion 205 of the switch about the 50 pivot end 204 in a counter-clockwise direction, causing the blade arm 206 to break contact with the terminals 217 and the blade-arm 207 to make contact with the terminals 220.

The terminals 217, as will hereinafter appear, 55 are in the circuit of the main drive motor 40, which drives the gears being burnished, lapped or tested, when the gears are rotating in the forward direction and the terminals 220 are in the circuit of the motor when the gears are being 60 driven in the reverse direction.

After plunger 230 has rocked the switch 205 to break contact with the terminals 217 and make contact with terminals 220, the plunger continues to move outwardly under actuation of the spring 65 233 until the teat 236 rides clear of the plunger 214. Then, of course the plunger 222 and spring 226 will rock the switch back in the opposite direction to break contact at the terminals 220 and make contact again with the terminals 217. 70

To insure that the contact points 212 and 213 will make contact with the terminals 220 long enough to insure starting of the drive motor in the reversed direction, the end of the plunger 230 is formed with a shoulder 240 and the tip of the 75

lug or cam 200 is beveled off as indicated at 242. As the cam shaft 99 rotates, then, the cam first engages the end of the plunger 230 pushing the plunger far enough in to engage the teat 236 behind the plunger 214. Then in the continued rotation of the cam shaft, the cam 200 rides clear of the end of the plunger and allows the plunger to move outwardly under actuation of the spring 233 causing the switch to break contact with the terminals 217 and make contact with the terminals 220 but when the cam 200 rides clear of the end of the plunger 230, it engages the shoulder 240 of the plunger and the outward movement of the plunger under actuation of the spring 233 is halted. The beveled portion 242 of the cam engages the shoulder 240 of the plunger for a long enough interval to assure that the reverse drive is started. Then the bevel portion 242 of the cam 200 rides clear of the shoulder 240 of the plunger 20 and the plunger completes its movement to the right under actuation of the spring 233, breaking contact at the terminals 220 and making contact again at the terminals 217 in the manner already described.

25 The single blade switch which controls the stopping of the machine comprises a body portion 245 and a blade-arm 246 which is pivotally mounted at 247 on the body portion 245. The body portion 245 is pivotally mounted upon a pin 248 in the switch box 209. The switch arm carries a bar 250 which is provided with contact points 252 and 253 (Figs. 7 and 18) that are adapted to make contact with terminals 254 (Figs. 18 and 25). When contact of the points 252 and 253 with the terminals 254 is broken, the machine stops.

There is a spring pressed plunger 256 slidably mounted in the body portion 245 of the switch. A coil spring 258 is interposed between the plunger 256 and blade-arm 246 and serves to urge the plunger downwardly and outwardly and the blade-arm upwardly into operative position. A spring pressed plunger 260 is pivoted to the body portion 245 of the switch at 261. This plunger is housed and slides in an opening 262 in the end plate 225 and is pressed upwardly by the coil spring 263 which surrounds the stem of the plunger. This spring presses the plunger upwardly to normally rock the body portion 245 of the switch about its pivot 248 to hold the switch closed.

The body portion 245 of the switch is rocked in a counter-clockwise direction to open the switch by operation of a spring pressed plunger 265. This plunger is housed in an opening in the end plate 225 and slides therein. It is pressed outwardly by a coil spring 266 which surrounds the stem of the plunger and is interposed between a shoulder on the plunger and a cap-plate 267 which is secured 60 to the cover plate 225.

There is a teat 268 formed on one side of the plunger 265 near the outer end thereof. This teat has a beveled end. When the cam 201 engages the plunger 265 in the rotation of the cam shaft 99, the plunger is forced inwardly against the resistance of the spring 266 and the teat 268 rides under the plunger 256 which has a beveled tip complementary to the beveled tip of the teat. When the cam 201 has rotated clear 70 of the end of the plunger, the spring 266 forces the plunger outwardly again but at this time the teat 268 is engaged behind the plunger 256 and so the switch is rocked about its pivot 248 causing the contact points 252 and 253 to be disengaged from the terminals 254. This opens the

circuit of the machine as will be described more particularly hereinafter, and stops the machine. As the plunger 265 continues to move outwardly under actuation of the spring 266, the teat 268 clears the plunger 256 and the spring pressed 5 plunger 260 operates again to close the switch.

A dash-pot is provided in conjunction with the plunger 260 so as to prevent the switch being closed again before the circuit to the controllers of the machine has actually been broken. This 10 dash-pot comprises a plate 270 (Fig. 18) which is secured between a shoulder on the stem of the plunger and the nut 271. The plate 270 slides in a chamber or recess 272 and has substantially air-tight engagement with the walls of this 15 chamber. There are holes 273 through the plate. Above the plate there is a disc 275 slidably mounted on the stem of the plunger and having a limited movement thereon. When the plunger 260 moves downwardly on the opening of the switch, 20 air passes freely through the openings 273 in the plate 270 and the movement of the plunger is not restricted but when the plunger moves upwardly again to reclose the switch, the disc 275 rests on the top of the plate 270 closing the openings 273 and air is entrapped between the plate 270 and the inner end wall of the chamber 272 and so the upward movement of the plunger is retarded preventing re-closing of the switch until sufficient time has elapsed for the controller to 25 function and actually stop the machine.

To prevent the lapping or burnishing compound from being sprayed about and to protect the operator against injury during burnishing or lapping a guard is provided to enclose the gears 35 during the burnishing or lapping operations. This guard comprises a fixed housing 280 (Figs. 1 and 13) and a door or closure 282 that is pivotally mounted on the housing 280. The fixed housing 280 is secured to the base 30 of the machine in any suitable manner in position to enclose the gear and pinion being burnished or lapped as shown in Fig. 2. The door 282 permits of access to the gears, removal of the gears after the burnishing or lapping operation has 40 been completed and chucking of gears for a new 45 operation.

The door 282 is pivotally mounted upon the fixed housing 280 by means of a pin or bolt 283. A coil spring 284, which surrounds this bolt, has 50 one end in engagement with the door and the other end in engagement with the fixed housing and serves to hold the door in any position to which it is moved. A handle 285 is secured to the door at one side thereof to permit easy manipulation of the door.

The lapping compound is pumped onto the gears by a pump shown in dotted lines in Fig. 1 which is driven by a motor 285'. The pump forces the lapping compound through the line 60 287 (Fig. 13) and the pipes 288 and 289, which are secured in the housing 280 into an elbow 290 (Figs. 13 and 14). The elbow 290 has one or more openings 292 in it through which the lapping compound may drop into a funnel-shaped 65 receptacle 293. This receptacle is secured by screws 294 to the door 282 and it has a flexible hose 295 connected to it and leading from it. The nozzle 296 of this flexible hose is held in a bracket 297 that is vertically and horizontally adjustable 70 upon a second bracket 298 which is horizontally adjustable upon a supporting plate 299. The supporting plate 299 is clamped to ribs 300 formed on the door 282 by clamping-gibs 302 and screws 303 and the supporting plate is horizontally ad- 75

justable on the ribs 300 in a direction at right angles to the direction of adjustment of the bracket 298 on the supporting plate 299.

The bracket 297 is secured to the bracket 298 in any position of its adjustment thereon by the bolt 304 which passes through the vertical slot 305 in the bracket 297 and the horizontal slot 306 in the bracket 298. The bracket 298 is secured to the supporting plate 299 in any position of its adjustment thereon by bolts 308 which pass through horizontal slots 309 in a projecting portion 310 of the supporting plate.

The various adjustments described permit of directing the lapping compound, when the door 282 is closed, onto the gears being lapped at the most desirable point for the lapping process.

The portion of lapping compound pumped up by the pump and which does not flow out through the opening 292 flows on through the elbow 290 into a return pipe 315 which carries the compound past the gears and allows it to drop into the bottom of the fixed guard 280 whence it is returned to the sump of the pump system by the return pipe 316. The pipe 288 is ordinarily long enough so that the pipe 290 projects forwardly in the housing 280 beyond the gears being lapped. Hence, when the door 282 is open, the compound dripping through the openings 292 in the elbow 290 simply falls into the bottom of the fixed housing 280 and is also returned to the sump by the pipe 316.

To prevent the machine from being operated for a lapping or burnishing process without the door 282 being closed, a double-throw limit switch 320 is mounted on the fixed housing 280. This switch is so mounted that the roller 321 carried by its switch arm 322 must be engaged by the flange of the door 282 to close the switch before the motors 40 and 60, which drive the gears and effect the burnishing or lapping motions, respectively, can be started as will be described more in detail hereinafter.

For applying a load to the gears during testing, a standard hand-brake may be employed such as illustrated in the patent to Slade No. 1,796,484 above mentioned. It is manipulated by the lever 325 (Fig. 2). This brake will operate upon the brake-drum 184 (Fig. 3) but as the construction of the same forms no part of the present invention, it will not be described in detail here.

To obtain a smooth, uniform motion during burnishing or lapping and to prevent back-lash between the gears accentuating the errors which it is desired to burnish or lap away, it has been found desirable in practice on lapping and burnishing machines to provide a back-lash brake which will exert a moderate pressure between the gears throughout the whole of the burnishing or lapping operation. An improved form of back-lash brake has been provided upon the present machine and this will now be described. 330 (Figs. 9 and 10) denotes a housing or sump which is secured to the end or cover plate 332 of the hand brake mechanism (Fig. 3) by bolts 334 (Fig. 10). The end plate 332 is secured to the guard 335 of the hand brake mechanism by screws 336 which thread into lugs formed integral with this guard. The guard is secured to the spacer-member 180 by screws 338 which pass through lugs in the guard and thread into the spacer-member. The cylinder 331 which houses the chuck-release piston 58 is secured to the housing 330 by screws 333.

A gear pump 340 of any usual or suitable construction is mounted upon a bracket 341 which

is secured by screws 342 to the housing 330 at one side thereof. The pump 340 is driven from the gear spindle 48 through a pulley 337 which is fastened to the spindle, a pulley 339 which is fastened to the motor shaft of the pump, and the belting 343 which connects the two pulleys. 5

Flexible hose 344 and 345 are connected to opposite sides of the pump. The hose 344 is connected by an elbow 346 with a duct 347 formed in one wall of the casing 330. The duct 347 connects with a well 348 formed in the bottom of the casing 330 (Figs. 9 and 11). There are two parallel ducts 349 and 350 that lead downwardly from this well. The duct 349 communicates with a duct 351 which is normally closed by a relief valve 353. This relief valve is slidable in the duct 351 and in aligned openings formed in the bottom of the casing 330. It is normally held in closed position by a coil spring 354, the tension of which may be adjusted by the screw 355 which is operated by the hand wheel 356. 10

The valve 353 has openings 358 therein which permit liquid to flow from the duct 351 into the sump 360 when the valve is forced open by pressure of oil flowing into the duct 351 through the line 344 from the exhaust side of the pump 340. 15

When the line 344 is on exhaust, the duct 350 is closed by a ball check valve 361 that shuts off communication between the duct 350 and a duct 362 which leads into the sump. When the pump 340 is rotating in the opposite direction, however, and the line 344 is on suction, the valve 361 is open and oil is drawn from the sump 360 into the pump. 20

The hose 345 connects with a duct 363 which is similar to the duct 347 and this duct connects with a well which is similar to the well 348 and from which there lead two ducts similar, respectively, to the ducts 349 and 350 and closed respectively, by a relief valve and a ball check valve 40 similar, respectively, to relief valve 353 and ball check valve 361, respectively. The two ducts communicate, respectively, with the sump 360 when the relief of ball check valve, respectively. are open. The hand wheel for controlling the tension of the relief valve associated with the line 345 is designated at 365. 35

When the gear spindle 48 is rotating in one direction the pump 340 is so driven that it sucks oil from the sump through the ball check valve 50 361, ducts 350, well 348, duct 347, elbow 346 and piping 344 and it exhausts this oil through the piping 345 and duct 363 and a relief valve corresponding to the relief valve 353 back to the sump. 55 In this direction of rotation of the spindle, the speed of rotation of the pump and therefore of the spindle is determined by the adjustment of the hand wheel 365 and of the relief valve controlled thereby. Hence, any desired load may be applied to the spindle 48 when rotating in the 60 described direction.

When the gears and spindle 48 are rotating in the opposite direction, oil is sucked from the pump 340 through a ball check valve corresponding to the ball check valve 361, the duct 363 and 65 the line 345 and is exhausted from the pump through the line 344, duct 347, well 348, duct 349, relief valve 353 and the openings 358 in that valve back to the sump. The rate of rotation of the pump and of the spindle 48 is then determined by the adjustment of the relief valve 353 through the hand wheel 356. By the mechanism described, then, any suitable load can be applied to the spindle 48 and to the gears being burnished or lapped during rotation of the gears in 70 75

either direction. Pressure gauges 373 and 373' are provided to permit determining the brake-load in either direction accurately.

- One of the features of the present machine is the incorporation in the means for adjusting the pinion head 31 of a dial gauge to permit precise adjustment of this head so that the pinion P may be adjusted accurately into correct meshing relation with the gear G for lapping or testing.
- 5 The pinion head 31 is adjustable by means of a screw shaft 370 (Fig. 12) that threads into a nut 371 which is secured to the pinion head. The shaft 370 has a sliding key connection with a sleeve 372 to which the hand wheel 374 is secured.
- 10 The pinion head 31 is also movable by means of a piston 375 which is connected to a piston rod 376 and is slidable in a cylinder 395 that is secured in any suitable manner to the base of the machine. The piston rod 376 is connected to a yoke member 378 by a nut 377. This yoke member is connected through ball thrust bearings 379 and 380 and the nut 382 to the screw shaft 370.
- 15
- 20
- 25
- 20 The piston 375 may be operated by a rotary control valve and an inching valve such as described in Patent No. 1,881,999. As these valves form no part of the present invention they will not be described here.

- Secured in any suitable manner to the yoke member 378 is a plate 385. This plate has a hook 386 at one end. The hook is adapted to engage the short arm of a magnifying bell-crank lever 387 that is pivoted at 388 on a guard 389 which is secured to the base or frame 30 of the machine. The long arm of the bell crank lever 387 engages 35 at its tip with the contact point of a dial gauge 390 which may be of standard or any suitable construction and which is also mounted in the guard 389. A glass sight 392 is provided in the guard to permit the operator to readily read the dial gauge.

- For precision lapping or testing, it is desirable to have the gears being lapped or tested meshed very accurately as to depth. This is done in the present machine by first finding precisely the bottoming position of the pinion in the gear, that is, the position in which the tops of the pinion teeth bottom in the tooth spaces of the gear and by then backing the pinion out of bottoming position the predetermined distance required until 45 the pinion will run with the gear in the desired depth-wise mesh relation.

- To find the bottoming position of the pinion, the teeth of the gear are aligned with the tooth spaces of the pinion and the pinion head 31 is 50 inched on to the limit of movement of the piston 375 in its cylinder 395 to engage the teeth and tooth spaces of the pair in mesh. The piston in its movement carries the piston rod 376 and yoke-member 378 with it and the yoke member carries the screw shaft 370, sliding this shaft in the sleeve 372. Just before the piston 375 has reached its limit position, the hook 386 on the plate 385 will engage the short arm of the lever 387 and impart movement to the contact point of the gauge 55 390, which movement will be registered by the gauge. When the piston 375 has reached the limit of its movement to the right, the operator moves the pinion head 31 on to bottom the pinion in the gear by rotation of the hand wheel 374. When the teeth of the pinion teeth actually 60 strike the bottoms of the tooth spaces of the gear, the shock will be transmitted back through the head 31, nut 371 and screw shaft 370 and will cause a slight deflection of the yoke member 378. This will cause the hook 386 to move to the

left. This slight movement will be reflected through the magnifying lever 387 to the dial gauge and the operator will know immediately that he has reached bottoming position. The operator will then rotate the hand wheel 374 to back the pinion away from the gear a pre-determined distance to the point where the pinion and gear will run accurately together, ordinarily to the position where they have true pitch-line mesh. In this backing-away movement, the head 31 will be moved relative to the piston 375, for the shaft 370 will rotate in the nut 371. The amount of the backing-away movement may be determined accurately by reading the micrometer dial 396. This dial is graduated to read 15 against a zero mark on the end plate 397 of the cylinder 395.

Having precisely determined the correct position of mesh of one pair of gears, the settings of the screw shaft so determined will do for any 20 pair of identical meshing gears and thereafter any pair of identical gears may be brought into correct depthwise meshing relation simply by inching the piston 375 on to the limit of its movement in its cylinder. It is only necessary to make a 25 new precision setting when a different ratio of gears is to be lapped or tested.

For lapping, as has been described, the gear and pinion are rotated together in mesh and simultaneously the carrier 52 is oscillated to impart an eccentric motion to the gear and the quill 51 is reciprocated to impart a depthwise movement to the gear. For testing, the gears are simply run together in mesh and the oscillating motion of the carrier and the reciprocating 35 motion of the quill are omitted. One way in which a combination lapping and testing machine may be wired to accomplish the purposes of the present invention is illustrated diagrammatically in Fig. 25. The lapping circuit will be 40 described first.

At some convenient point on the machine there are secured an electric start button 400 and an electric stop button 401 (Fig. 25). The start button is a normally open button and the 45 stop button is a normally closed button. For lapping, the door 282 (Fig. 13) of the guard 280 must be closed before the machine can be started so that the switch 320 is in the position shown in Fig. 25 with the bar 402 bridging the terminals 403 and 404. The axial position of the shaft 99 must also be such that the cam 132 (Fig. 7) is in engagement with the roller 135 so as to be able to impart the oscillating movement to the carrier 52. In this position of the shaft, the 55 switch 196 will occupy the position shown in Fig. 25 with the bar 406 bridging the terminals 407 and 408. The reversing switch 205 will be in the position shown in the Figs. 17 and 25 with the bar 216 and the contact points carried thereby 60 bridging the terminals 217. The stop switch 245 will be in the position shown in Figs. 18 and 25 with the bar 250 bridging the terminals 254.

When the operator presses the starting button 400 a circuit is made from the main line L₁ through the line 410, the terminals 403 and 404 and the bar 402, the line 412, the line 413, the line 414, the terminals 415 and 416 and the starting button 400, the line 418, the solenoid-coil 420, the line 421, the line 422, the terminals 423 70 and 424 and the stop button 401, the line 425, the terminals 254 and the bar 250 of the stop switch 245, the line 426, the terminals 427 and 428 and the bar 429 of the reverse controller for the main drive motor 48 of the machine, the line 75

430, the terminals 431 and 432 and the bar 433 of the forward controller for the motor 40, the line 435, the terminals 436 and 437 and bar 438 of a controller for the oscillating drive motor 60 (Fig. 5 7), to the main line L₂. This circuit energizes the coil 420 to close a two-pole normally open relay 440.

As soon as the relay 440 is closed, a circuit is made which energizes the forward and oscillating controllers. The circuit to the forward controller is from the main line L₁ through the line 442, the terminals 443 and 444 and the bar 445 of the relay 440, the line 446, the coil 447 of the forward controller, the line 448, the line 422, stop button 15 ton 401 and the lines previously described to the main line L₂. The circuit to the oscillating controller is made from the main line L₁ through the line 452, the terminals 453 and 454 and bar 455 of the relay 440, the line 456, coil 457 of the oscillating controller, and line 458 to the line 448 and thence through the line 422 and stop button 401 to the main line L₂ in the manner already described.

The energized coil 447 pulls the switch-blades 25 460, 461, and 462 closed so that they make contact with the terminals 464, 465 and 466, respectively and close a circuit to the main drive motor 40 (Fig. 1) through the forward controller and the lines 468, 469, and 470. This starts the motor 30 40 driving the meshing pinion P and the gear G in the forward direction. At the same time that the energized coil 447 closes the switch arms 460, 461 and 462 it also closes the switch arm 472.

The energized coil 457 closes the switch arms 35 475, 476, and 477 and also the switch arm 478 so that these arms make contact, respectively, with the terminals 480, 481, 482, and 483 of the oscillating controller. The closed switch arms 475, 476, and 477 make a circuit through the oscillating controller and the lines 485, 486, and 487 to the oscillating drive motor 60 (Fig. 7) and this motor through the drive already described oscillates the carrier 52 and reciprocates the quill 51 in the carrier, thus imparting a combined eccentric and 45 axial motion to the gear G with reference to the pinion P.

Now the start button 400 is a normally open button. Therefore when the operator takes his finger off of the start button it flies open. This 10 breaks the circuit to the coil 420. The relay 440 is a normally open relay. Hence when the circuit to the coil 420 is broken, the relay 440 opens. This breaks the described circuit to the coils 447 and 457, but the circuit to these coils is now maintained through the switches 472 and 478, respectively, and so the motors 40 and 60 are not stopped.

The circuit to the coil 447 is maintained from the line L₁ through the line 410, terminals 403 60 and 404 and bar 402, line 411, terminals 408 and 407 and bar 406, line 412, line 490, line 491, terminals 492, switch arm 472, line 494, terminals 217 and bar 216 of switch 205, line 495, line 448, the coil 447, lines 448 and 422, through the stop button 65 ton 401 and the already described connections to the main line L₂. The circuit to the coil 457 is maintained from the main line L₁ through the described connections with the lines 412 and 490, the line 491, terminal 483, switch 478, line 498, 70 coil 457, lines 458, 448 and 422 and stop button 401 through the already described connections to the main line L₂.

The described circuits to the main drive motor 40 and oscillating motor 60 are maintained until 75 the cam 280 (Figs. 7 and 18) trips the switch 205,

breaking contact of the bar 216 with the terminals 217 and causing contact to be made between the bar 218 and the terminals 220.

When contact of the bar 216 with the terminals 217 is broken, the coil 447 is de-energized; the switch arms 460, 461, 462, and 472 open and the main drive motor 40 stops. As soon as the contact bar 218 makes contact, however, with the terminals 220, the main drive motor is re-started but in the reverse direction. The closing of the 10 contact of the bar 218 with the terminals 220 causes a circuit to be made from the line L₁ through the line 410, the terminals 403, and 404 and bar 402 of switch 320, the line 411, terminals 408 and 407 and bar 406 of switch 196, 15 line 412, line 413, line 500, terminals 220 and bar 218 of switch arm 207, lines 501 and 502, coil 503 of the reverse controller line 504, and lines 448 and 422 through the stop button 401 and the previously described connections to the main line 20 L₂. This energizes the coil 503 closing the switch blades 505, 506 and 507 and also the switch blade 508.

The switch blades 505, 506, and 507 make contact with the terminals 510, 511, and 512, respectively, causing the main drive motor 40 to be driven in the reverse direction through the lines 514, 515, and 516.

As already described, the nose of the cam 200 contacts with the shoulder 240 of the plunger 30 230 (Fig. 17) only long enough to insure restarting of the drive motor 40 in the reverse direction. Then the nose of the cam slips off of the shoulder of the plunger and contact of the bar 218 of the switch 205 with the terminals 220 is 35 again broken. The circuit to the coil 503 is maintained, however, from the line L₁ through the line 410, switch 320, line 411, switch 196, line 412, line 490, terminal 520, switch 506, coil 503, lines 504, 448, and 422 and stop button 401 and connections already described to the main line L₂.

The main drive motor 40 continues to drive the pinion P and gear G in the reverse direction until the cam 201 (Fig. 18) trips the switch 245. Then the circuit to the coils 503 and 457 through the stop button 401 is broken and both motors 40 and 60 are stopped. This stops the machine with its operations completed in one revolution of the cam shaft 99. The stop switch 245 closes again automatically but its re-closing is retarded 50 sufficiently by the dash-pot plate 210 to insure breaking of the circuit to the coils 503 and 457 and opening of the switch arms 508 and 478. Hence, on the re-closing of the switch 245, the motors 40 and 60 are not restarted, nor can 55 they be restarted until the start button 400 is again pushed in and when the start button 400 is again pushed in, the machine will go through its full cycle.

In order to use the machine for testing gears, 60 the cam shaft 99 must be shifted axially by the lever 153 (Fig. 7) to disengage the cam 132 from the roller 135 and bring the concentric disc 131 into engagement with this roller for in the testing operation, the gear G and pinion P are 65 run together in fixed positions and neither an oscillating motion nor an axial motion of the gear is desired. In testing, also, the door 282 of the guard 280 (Figs. 1 and 13) will be open.

When the cam shaft 99 is shifted to engage 70 the roller 135 with the disc 131, the arm of the switch 196 will be moved to cause the bar 406 of this switch to break contact with the terminals 407 and 408 and to cause the bar 526 of this switch to make contact with the terminals 75

526 and 527. When the door 282 of the guard 280 is opened, the arm of the switch 320 will rock automatically to cause the bar 402 to break contact with the terminals 403 and 404 and 5 cause the bar 528 of this switch to make contact with the terminals 529 and 530. The machine is now in condition for testing gears.

There are two start buttons provided for the testing operation. One of these buttons, 532 is 10 used to permit testing the gears while rotating forwardly and the other of these buttons, 533 is used for testing the gears in reverse. Both are normally open buttons.

When the button 532 is pushed in, a circuit is 15 made from the line L₁ through the line 535, the terminals 529 and 530 and bar 528 of the switch 320, the line 536, the terminals 527 and 526 and the bar 525 of the switch 196, the line 537, the terminals 538 and 539 and the start 20 button 532, the line 540, the line 446, the coil 447, lines 448 and 422, stop button 401 and the already described connections to the main line L₂. This energizes the coil 447, closing the blade arms 460, 461, and 462 and starting the motor 25 40 to drive the pinion P and gear G in the forward direction for test.

When the start button 533 is pushed in, a circuit is made from the line L₁ through the line 535, the switch 320, the line 536, the switch 196, the line 537, the line 542, the terminals 543 and 544 and the start button 533, line 545, line 502, coil 503 and lines 504, 448 and 422, stop button 401 and the connections already described to the main line L₂. This energizes the 35 coil 503 to close the switch arms 505, 506 and 507 and cause the main drive motor 40 to be driven in the reverse direction.

It will be noted that during testing, the motor 40 will operate only so long as the button 532 40 or button 533 is closed and as both these buttons are normally open buttons, the operator must keep his finger on one or the other of these buttons in order to continue the test. This keeps one hand of the operator continuously occupied 45 during testing of a pair of gears. Since his other hand will be employed manipulating the hand-brake lever 325 (Fig. 2) to apply a load to the gears during the test it will be seen that the operator is fully protected against any possibility 50 of getting his hand caught between the gears during testing. Such possibility is, of course, obviated during lapping or burnishing because the door 282 of the guard 280 must be closed during either of these operations.

55 When the button 532 is pushed in, the coil 447 is energized to close the switch 472 as well as the switches 464, 465, and 466 but when the machine is in use for testing, this closing of the switch arm 472 does not complete a circuit to the coil 447 for the switch 196 is open at the terminals 407 and 408 and the switch 320 is open at the terminals 403 and 404. Hence, when the button 532 is released, the motor 40 stops its forward drive. Likewise when the button 533 is pushed in, no circuit is closed by the switch 508 to the coil 503 and this coil is only energized as long as the button is held in by the operator and when he releases the button the machine 65 stops.

70 It will be noted that the coil 457 of the oscillating controller is not energized either when the button 532 is pushed in or when the button 533 is pushed in, for neither of these buttons closes 75 a circuit to the coil 420 and so the relay 440

remains open. Hence, the oscillating motor 60 does not run during testing.

A combination burnishing and testing machine built according to the preferred embodiment of the present invention differs only from 5 the preferred form of combination lapping and testing machine in the omission of the positive means for reciprocating the quill 51. For burnishing, according to preferred practice, as already stated, the teeth of the pinion are bottomed in the tooth spaces of the gear and are held resiliently in such bottoming position while the pinion and gear rotate together and while the carrier 52 is oscillated to swing the gear about an axis eccentric to its own axis. 15

The preferred construction of the gear head on a burnishing machine is illustrated in Fig. 4. It will be noted by comparison with Fig. 3 that the screw shaft 175 and nut 178 and the parts for actuating the same have been omitted in the 20 burnishing machine. Different springs, differently located are also employed on the burnishing machine to hold the gear resiliently in bottoming mesh with the pinion. In the burnishing machine a plurality of coil springs 550 are 25 mounted in aligned openings 552 and 553 in the carrier 52 and quill 51, respectively. They abut at one end against the bottoms of the opening 552 in the carrier and at their opposite ends against the plugs 554 which are secured in the 30 quill. They serve to urge the quill forwardly in the carrier and hold the gear in bottoming engagement with the pinion.

The operation of machines built according to the present invention will be understood from 35 the preceding description but may be briefly summed up here. Assuming that a pair of gears are to be lapped, the operator chucks the pinion P and the gear G. He then determines their correct depth-wise meshing position by the use 40 of the dial gauge and associated mechanism as described above with reference to Fig. 12, or, if the pair of gears to be lapped are simply one of a series of pairs for which the correct depth-wise lapping position has already been determined, simply brings the pinion P into mesh with 45 the gear G by causing the piston 375 to bottom in the right end of its cylinder 395. The proper cams 132 and 158 (Figs. 7 and 8) will also be secured on the cam shaft 99 and the proper 50 change gears 68, 69, 75, and 74 will also be selected. The shaft 99 is positioned axially by the lever 153 (Fig. 7) so that the cam 132 engages the roller 135. When the gears are in mesh, the door 282 of the guard 280 is closed. The 55 machine is now ready for operation.

The operator presses in the start button 400. This starts the main drive motor 40 in forward drive and the oscillating motor 60 through the electrical connections described with reference 60 to Fig. 25. The pinion and gear rotate in mesh, being driven from the motor 40 through the belt drive 41—43—42 and the drive spindle 36 (Fig. 1). The motor 60 drives the cam shaft 99 through the gearing 63, 64, 68, 74, 84, 87, 96, and 65 97 (Figs. 7 and 8) and the cam shaft 99 oscillates the carrier 52 through the cam 132, bar 138 and the yoke member 145 (Figs. 7 and 3). Simultaneously, also, the cam shaft reciprocates the quill 51 through the cam 158, bar 162, arm 70 165, screw shaft 175 and nut 178 (Figs. 3 and 7). Thus, as the gear G and pinion P rotate together, an oscillating movement is imparted to the gear G about the axis of the carrier 52, and simultaneously also a reciprocating axial movement is 75

imparted to the gear G through the movement of the quill 51 in the carrier. The oscillating movement is an eccentric movement because the axis of the gear spindle 48 is offset from the axis 5 of the carrier 52.

After the gears have rotated together in one direction for a suitable predetermined length of time, as determined by the ratio of the change gears 68—74, the cam 200 on the shaft 99 will 10 engage the plunger 230 (Fig. 17) and trip the switch 205, thus breaking the connection to the drive motor 40 and immediately re-starting this motor again but in the reverse direction through the electrical connections described with reference to Fig. 25. Simultaneously with the reversal 15 of the motor 40, the change gear drive to the cam shaft 99 is shifted. The pin 180 on the worm wheel 97 (Fig. 8) strikes the arm 103 of the yoke-member 105 and through the load and fire mechanisms described, shifts the gear 87 out of engagement with the gear 84 and into engagement with the gear 85.

When these shifts have been accomplished, the gear G and pinion P rotate in the reverse direction but the oscillation of the carrier 52 and reciprocation of the quill 51 continue so that as gear G and pinion P rotate in the reverse direction also, the gear G is oscillated eccentrically and reciprocated axially.

30 After the pinion P and gear G have been rotated together in the reverse direction for such predetermined length of time as fixed by the change gears 69 and 75, the cam 201 is brought by the rotation of the shaft 99 into engagement 35 with the plunger 265 (Fig. 18) and the switch 245 is tripped. This stops the machine as already described. The lapping operation is completed and the operator removes the pair of gears lapped and chuck a new pair.

40 The functions of the cam 158, screw shaft 175 and nut 178 in the lapping operation will be apparent from the diagrammatic views, Figs. 19 to 24 inclusive.

Figs. 19 and 20 show a bevel gear G and pinion 45 P in mesh in correct running position with their apices 560, 565 coinciding. The side surfaces 561 and 562 of a tooth space of the gear contact at a central area along the sides with the mating side surfaces 563 and 564, respectively, of a pinion 50 tooth. The tooth surfaces of gear and pinion are shown as provided with the usual amount of tooth surface mismatch to provide that localization 55 of tooth bearing required in practice.

The oscillating movement of the carrier 52 causes the gear to be moved out of true central meshing position with the pinion first toward the heel of the pinion teeth and then towards the toe of the pinion teeth and simultaneously to be 60 swung above and below center.

65 As the carrier 52 swings in one direction moving the gear toward the large end or heel of the pinion tooth, the bearing between the side surfaces of the gear and pinion teeth is displaced from the central position shown in Figs. 19 and 20 toward the outer or heel ends of the teeth as indicated in Figs. 21 and 22. In this movement, the apex 565 of the gear is displaced upward and horizontally from the apex 560 of the pinion. There would be interference between the convex 70 side 562 of the gear tooth and the concave side 564 of the pinion tooth at the toe of both if the gear were not withdrawn axially from the pinion. In the present machine, this necessary axial withdrawal of the gear is effected automatically 75

through operation of the cam 158 and of the screw shaft 175 which is actuated thereby.

When the carrier 52 swings in the opposite direction, the bearing between the gear and the pinion teeth is displaced toward the toe or front 5 end of the teeth, as indicated in Figs. 23 and 24 and the apex of the gear is displaced in the opposite direction from the apex of the pinion. In this movement, interference is likely to develop, as indicated in Fig. 23, between the concave surface of the pinion tooth and convex surface of the gear tooth at the heel of both. This interference is avoided automatically in the lapping machine of the present invention by automatic withdrawal of the gear axially through movement of the quill 15 51 under actuation of the cam 158 and screw shaft 175.

In the lapping machines of Patents Nos. 1,796,484 and 1,881,999 above mentioned, there 20 was no provision for an automatic axial movement of the gear during oscillation of the gear carrier. Hence in setting up these previous machines for a lapping operation, the pinion was meshed with the gear at a shallow enough depth 25 to insure that at both ends of swing of the gear carrier, there would be no interference between the gear and pinion tooth surfaces. The result of such a setting, however, was that when the gear and pinion were in a central position, corresponding to the position of Fig. 19, the gear was withdrawn from the depthwise engagement with the pinion more than necessary and in this position there was an excessive amount of back-lash between the gear and pinion teeth and, moreover, lapping could not be carried on to as great depth 30 as by the mechanism of the present invention. The lapping machine of the present invention provides an automatic depthwise adjusting mechanism which permits of automatically avoiding interference between the gear and pinion teeth 40 and maintains a uniform amount of back-lash throughout the lapping operation.

A burnishing machine constructed according to the preferred embodiment of the present invention will operate exactly as does the preferred 45 embodiment of lapping machine described, except that the controlled depthwise movement of the gear is omitted. Instead, the gear and pinion are meshed with the teeth of the pinion bottoming in the tooth surfaces of the gear and they are 50 held in this position resiliently by the springs 550 throughout the whole of the burnishing operation.

For testing a pair of gears either on a lapping machine or a burnishing machine, the operator 55 shifts the shaft 99 to engage the disc 131 with the roller 135 (Fig. 7) and opens the door 282 of the guard 280. For the testing operation, the gears are simply run together. The carrier does not oscillate and there is no axial movement of the 60 gear. To test the gears by running in the forward direction, the operator holds his finger on the start button 532 (Fig. 25) and with his other hand operates the brake lever 325 (Fig. 2) to apply a load to the gears. When the operator has 65 satisfied himself about the operation of the gears in the forward direction, he releases the start button 532. He may then test the gears for operation in the reverse direction by pushing in the starter button 533 and again manipulating the 70 brake lever 325. When the test in reverse is through the operator releases the starter button 533 and the machine stops.

While the invention has been described in connection with certain particular embodiments 75

thereof and particular uses, it will be understood that it is capable of various modifications and uses and that this application is intended to cover any variations, uses, or adaptations of the invention following, in general, the principles of the invention and including such departures from the present disclosure as come within known or customary practice in the machine tool art and as may be applied to the essential features herein before set forth and as fall within the scope of the invention or the limits of the appended claims.

Having thus described my invention, what I claim is:

1. The method of finishing tapered gears which comprises bringing a pair of tapered gears into mesh with their axes angularly disposed to one another and rotating the gears in mesh while moving one of the gears in the direction of the axis of the other gear and producing a relative movement between the gears in a direction transverse of said axis and simultaneously effecting a relative depthwise movement between the gears which is coordinated to the two last named movements so that as the tooth surfaces of one gear slide over the tooth surfaces of the other in these movements the amount of back-lash between the gears is maintained uniform.

2. The method of finishing tapered gears which comprises bringing a pair of tapered gears into mesh with their axes angularly disposed to one another and rotating the gears in mesh while oscillating one of the gears about an axis parallel to and eccentric of its own axis and simultaneously producing a positive relative movement between the gears in the direction of said axis.

3. The method of finishing tapered gears which comprises bringing a pair of tapered gears into mesh with their axes angularly disposed to one another and rotating the gears in mesh while oscillating one of the gears about an axis parallel to and offset from its own axis and producing a controlled relative depthwise movement between the gears to control the amount of back-lash between the gears throughout their other relative movements.

4. In a machine for finishing gears, a rotatable spindle, an oscillatable carrier, a second spindle eccentrically journaled in said carrier with its axis parallel to the axis of said carrier and angularly disposed to the axis of the first spindle, means for detachably securing a gear to each of said spindles, means for adjusting the spindles relative to one another to bring the gears carried thereby into mesh, means for rotating said spindles, means for oscillating said carrier and means for moving the second spindle axially in the carrier.

5. In a machine for finishing gears, a pair of spindles which have their axes angularly disposed to one another, an oscillatable carrier in which one of the spindles is journaled with its axis parallel to but offset from the axis of the carrier, means for detachably securing a gear to each spindle, means for rotating one of the spindles to rotate the gears in mesh, means for simultaneously oscillating the carrier, and means driven in time with the carrier oscillation for reciprocating the spindle, which is mounted in the carrier, axially during the oscillation of the carrier in order to maintain backlash between the gears uniform during said oscillation.

6. In a machine for finishing gears, a rotatable spindle, an oscillatable carrier, a second spindle journaled in said carrier with its axis parallel to but offset from the axis of said carrier and

angularly disposed to the axis of the first spindle, means for detachably securing a gear to each of said spindles, means for adjusting the spindles relative to one another, means for rotating the spindles in opposite directions, a rotatable cam controlling the oscillation of said carrier and having half of its track formed to control the oscillation of the carrier while the spindles are rotating in one direction and the other half formed to control the oscillation of the carrier while the spindles are rotating in the opposite direction, means for rotating the cam and means for automatically reversing the direction of rotation of said spindles at the time the second half of the cam track rotates into operative position.

7. In a machine for finishing gears, a rotatable spindle, an oscillatable carrier, a second spindle journaled in the carrier with its axis parallel to but offset from the axis of the carrier and angularly disposed to the axis of the first spindle, means for detachably securing a gear to each of said spindles, means for adjusting said spindles relative to one another to bring the gears into mesh, means for rotating the spindles in opposite directions to rotate the gears in opposite directions, means for producing relative movement between said gears as they rotate in mesh, a cam for controlling the last named means, said cam having half of its track formed to control the oscillation of said carrier while the spindles are rotating in one direction and the other half of its track formed to control the oscillation of said carrier while the spindles are rotating in the opposite direction, means for rotating the cam and means for automatically reversing the direction of rotation of said spindles when the second half of the cam track rotates into operative position.

8. In a machine for finishing gears, a pair of spindles that are angularly disposed to one another, means for detachably securing a gear to each of said spindles, means for adjusting said spindles relative to one another to bring the gears into mesh, means for rotating the spindles in opposite directions to rotate the gears in opposite directions, means for producing relative movement between the gears as they rotate in mesh, a rotatable control member governing said last named movement, two sets of change gears selectively engageable operatively with said control member to drive said control member at different speeds, means for reversing the direction of rotation of said spindles, and means operable upon said reversal to disengage one set of said change gears and bring the other set into operative position.

9. In a machine for finishing gears, a pair of spindles that are angularly disposed to one another, means for detachably securing a gear to each of said spindles, means for adjusting the spindles relative to one another to bring the gears into mesh, means for rotating the spindles to rotate the gears in mesh, cam-controlled means for effecting relative movement between said gears while they are rotating, means for driving said last named means at different speeds, means for automatically reversing the direction of rotation of the gears after they have rotated a predetermined length of time in one direction, and means operable automatically at the time of said reversal to effect a change in speed of drive of said cam-controlled means.

10. In a machine for finishing gears, a pair of spindles, means for detachably securing a gear

to each of said spindles, means for adjusting the spindles relative to one another to bring the gears into mesh, means for rotating said spindles to rotate the gears in mesh, means operable to produce an added relative movement between said gears, a rotatable cam-shaft, a cam secured thereto for controlling said relative movement, means operatively connected to said cam shaft to effect reversal of the direction of rotation of the gears when the cam shaft has made part of a revolution, and means operatively connected to said cam shaft to stop said machine when the cam shaft has made a complete revolution.

11. In a machine for finishing gears, a pair of spindles, means for detachably securing a gear to each of said spindles, means for adjusting the spindles relative to one another to bring the gears into mesh, means for rotating said spindles to rotate the gears in mesh, means operable to produce an added relative movement between said gears, a rotatable cam-shaft, a cam secured thereto for controlling said relative movement, means operatively connected to said cam shaft to effect reversal of the direction of rotation of the gears when the cam shaft has made part of a revolution, means operatively connected to said cam shaft to stop the machine when the cam shaft has made a complete revolution, and means for driving the cam shaft at different rates of speed when the gears are rotating in opposite directions, respectively.

12. In a machine for finishing gears, a pair of spindles, means for detachably securing a gear to each of said spindles, means for adjusting the spindles relative to one another to bring the gears into mesh, means operable to produce an added relative movement between said gears, a rotatable cam shaft, a cam secured thereto for controlling said relative movement, means operatively connected to said cam shaft to effect reversal of the direction of rotation of the gears when the cam shaft has made part of a revolution, means operatively connected to said cam shaft to stop the machine when the cam shaft has made a complete revolution, separate change gear drives for driving said cam shaft at different speeds, and means operable by the shaft in its rotation for disconnecting one of the change gear drives from the cam shaft and connecting the other operatively thereto when reversal of the gears occurs.

13. In a machine for finishing gears, a rotatable spindle, an oscillatable carrier, a quill reciprocably mounted in said carrier, means constantly urging said quill in one direction in said carrier, a second spindle rotatably mounted in said quill, means for detachably securing a gear to each of said spindles, means for adjusting the spindles relative to one another to engage the gears in mesh, means for rotating the spindles and means for simultaneously oscillating said carrier.

14. In a machine for finishing gears, a rotatable spindle, an oscillatable carrier, a quill reciprocably mounted in said carrier, a second spindle rotatably mounted in said quill, means for detachably securing a gear to each of said spindles, means for rotating the spindles, means for oscillating said carrier and means for reciprocating said quill.

15. In a machine of the character described, a pair of rotatable spindles, means for detachably securing a gear to each of said spindles, means for adjusting the spindles relative to one another to bring the gears into mesh, actuating means operable to impart an additional relative move-

ment between said spindles when they are rotating, said actuating means being mounted to be movable to and from operative position, a movable guard adapted to enclose said gears, electrically operated means for driving both said spindles and said actuating means, separate manually operable normally open start buttons for starting said electrical drive means when the actuating means is in operative position and when it is in inoperative position, respectively, and electrical control means incorporated with said start buttons in the electrical circuit to said electrical drive means and constructed so that if the actuating means is in operative position, said guard must be closed before the drive can be started and if the guard is open, the actuating means must be in inoperative position before the drive can be started and one of said start buttons must be kept closed to maintain the drive in operation.

16. In a machine for finishing gears, a frame, a head mounted on the frame, a quill slidably mounted on said head and axially movable thereon, a spindle journaled in said quill, a second head mounted on the frame, a spindle journaled in said second head with its axis angularly disposed to the axis of the first spindle, means for detachably securing a gear to each of said spindles, means for adjusting the heads relative to one another to bring the gears into mesh with the top of the teeth of one gear bottoming in the tooth spaces of the other gear, means for rotating said spindles to rotate the gears in mesh and means resiliently operable on said quill to hold the gears resiliently in the described position of adjustment while they rotate together.

17. In a machine for finishing tapered gears, a pair of spindles angularly disposed with reference to one another, means for detachably securing a tapered gear to each of said spindles, means for adjusting said spindles relative to one another to bring the gears into mesh, means for rotating the spindles, and means for moving one of the spindles axially and in two directions each at an angle to its own axis during the rotation of the spindles.

18. In a machine for finishing tapered gears, a pair of spindles having axes angularly disposed to one another, means for detachably securing a gear to each of said spindles, means for adjusting said spindles relative to one another to bring the gears into mesh, means for rotating the spindles, means for simultaneously effecting a relative movement between said spindles to move the teeth of one gear longitudinally of the teeth of the other gear, and means for maintaining uniform back-lash between said gears during said movement.

19. In a machine for finishing tapered gears, a pair of spindles having their axes angularly disposed to one another, means for detachably securing a gear to each of said spindles, means for adjusting the spindles relative to one another to bring the gears into mesh, means for rotating the spindles, means for effecting simultaneously a relative movement between said spindles to move the teeth of one gear longitudinally of the teeth of the other gear, and means for moving one of said spindles to effect a relative depthwise movement between the teeth of said gears during the last named movement to maintain uniform back-lash between the gears.

20. In a machine for finishing tapered gears, a pair of spindles having their axes angularly dis-

posed to one another, means for detachably securing a gear to each of said spindles, means for adjusting said spindles relative to one another to bring the gears into mesh, means for rotating the spindles, means for simultaneously producing an additional relative movement between the gears in the direction of the axis of one of said spindles, and means for maintaining uniform back-lash between said gears during said last named movement.

21. In a machine for finishing tapered gears, a pair of spindles having their axes angularly disposed to one another, means for detachably securing a gear to each of said spindles, means for adjusting said spindles relative to one another to bring the gears into mesh, means for rotating the spindles, means for simultaneously producing additional relative movements between the gears in the direction of the axis of one of the spindles and in a direction at right angles there-

to, and means for maintaining uniform back-lash between the gears during said described movements.

22. In a machine for finishing tapered gears, a pair of spindles having their axes angularly disposed to one another, an oscillatable carrier, a quill in which one of said spindles is journalled with its axis parallel to but offset from the axis of the carrier, said quill being reciprocably mounted in said carrier for movement axially of the spindle which is journalled therein, means interposed between the quill and carrier for resiliently urging the quill in one direction in the carrier, means for detachably securing a gear to each of said spindles, means for adjusting the spindles relative to one another to engage the gears in mesh, means for rotating the spindles, and means for oscillating said carrier.

ROBERT S. CONDON. 20
